SIGN

Horace N. Carver, Wichita, Kans.

Application September 15, 1937, Serial No. 163,981

5 Claims. (Cl. 40—135)

This invention relates to signs and more particularly to a sign having reflecting characteristics which especially adapts it for use as a thoroughfare direction or warning signal.

5 The principal object of the present invention is to provide a sign adapted to efficiently reflect and/or refract light therefrom for attracting the attention of motorists and conveying suitable information to such motorists.

10 Other important objects of the present invention are to provide a sign of durable character and arresting appearance; to provide an improved reflecting panel for the sign; to improve the panel supporting elements; to provide protective features for the sign; to increase the brilliance of the sign; and to render the sign visible from a great distance.

In accomplishing these and other objects of the present invention, I have provided improved 20 details of structure, the preferred forms of which are illustrated in the accompanying drawing wherein:

Fig. 1 is a perspective view of a sign embodying the features of the present invention.

25 Fig. 2 is a vertical cross-section through the sign on the line 2—2, Fig. 1.

Fig. 3 is a horizontal cross-section through the sign on the line 3—3, Fig. 1.

30 Fig. 4 is a detail perspective view of the sign illustrated in Fig. 1 showing the parts thereof in disassembled spaced relation.

Fig. 5 is a detail vertical cross-section through a portion of a reflecting panel illustrating the pebbled outer surface of the panel and a lustrous 35 element on the inner surface of the panel.

Fig. 6 is a detail vertical cross-section through a portion of a reflecting panel illustrating the pebbled outer surface thereof and a prismatic inner surface for the panel.

40 Referring more in detail to the drawing:

1, Fig. 1, generally designates a sign embodying the features of the present invention which preferably consists of a post 2 or the like adapted to be suitably mounted in the ground at a strategic position in a road system, and 3 designates a support in the nature of a backboard which is fixed to the post 2 as by fastening devices 4. The support 3 may be of any suitable design and, in the present instance, it is shown as of octagonal shape having a suitable border portion 5, which may be of a color different from that of the support for enhancing the appearance of the sign and for providing a stop at the inner edges 6 thereof for centering a stencilled member 7 to be mounted on the support.

The stencilled member 7 is preferably of rectangular shape and provided with tapered side and end walls 8 engageable with the support in such a manner as to space the outer face 9 of the stencilled member outwardly relative to the outer face 10 of the support 3, the stencilled member being suitably secured to the support as by fastening devices 11. Cutout portions or perforations 12 are provided in the stencilled member in such a manner as to effect a legend 10 for the sign which, in the present instance, comprises the word "Stop", such cutout portions 12 preferably being provided with outstruck peripheral flanges 13 forming a protective element for the sign and enhancing its appearance. Ribs 14 are mounted in the cutout portions of the stencilled member and connected to the body portion thereof for connecting intermediate portions of the indicia formed by the perforations of the stencil and supporting parts of the indicia in 20 operative position relative to the cutout portions; for example, the center 15 of the letter "O" is in the word "STOP". The ribs 14 may be provided with a lustrous finish as by forming the same of polished aluminum for the purpose of 25 reflecting light rays impinging against the sign and the ribs of the letters in the stencilled portion thereof.

Mounted in the space between the face 10 of the support 3 and the inner face 17 of the stencilled member is a panel 18, which is preferably formed of a transparent or translucent material, such as glass or a suitable synthetic resin having a high tensile strength. The panel 18 may be in a single sheet of material, as shown, or, in 30 order to save material, may be composed of a plurality of individual panels mounted in the space between the support and stencilled member adjacent the respective indicia of the member to form backing elements for each of the 35 respective indicia of the sign. The panel 18 is preferably provided with a pebbled outer surface 19, as particularly shown in Fig. 5, which adapts the panel 18 for receiving light rays from practically any angle of incidence of such rays, at 40 a position forwardly of the sign, and disseminating the light rays throughout the panel in broken-up or multiplied form.

While the support 3 is adapted to reflect the disseminated light rays in some measure, it is 50 desirable to additionally promote reflection of such light rays and I, therefore, provide the inner surface 20 of the panel, in one embodiment of the invention as particularly shown in Fig. 5, with a lustrous finish or coating 21, which may 55

be, for example, the aluminium preferably used on the ribs 14 of the stencilled member, or which may be in the form of gold or silver leaf or paint, or even the usual mirrored backing of mercury and/or silver containing substances. When the lustrous finish 21 is used for effecting reflection of light rays in the panel 18, a protective coating 22, such a lead paint, is also provided on the panel in covering relation to the lustrous coating 21 for protecting and conserving such lustrous finish.

Another embodiment of the panel is disclosed in the panel 23 illustrated in Fig. 6, which is provided with a pebbled outer surface 24 as has been previously described, but which is provided with a prismatic rear face 25 for refracting the light rays entering the pebbled surface 24 of the panel and additionally disseminating such rays and refracting the rays for reflecting them out of the panel again in intensified form to attract the attention of motorists and convey suitable information to such motorists. The inner surface 25 of the panel illustrated in Fig. 6 is also preferably provided with a lustrous finish or coating 25' such as that described in connection with the plane inner face 21 of the panel illustrated in Fig. 5. It has been found that such a coating prevents collection of dust and moisture between the angles of the reflecting surfaces of the prisms and thus enhances their action in reflecting and refracting light rays. A protective coating 25" may also be provided for the lustrous coating.

In order to further protect the panel or panel parts of the sign, I preferably provide the stencil perforations 12 with a suitable screen 26 as of wire mesh which, in the present instance, is shown as composing individual parts engaged within the stencil openings. The screen may be provided with a lustrous finish as by polishing the wire from which it is made for enhancing reflection of light from the sign.

The assembly and operation of the sign disclosed in Figs. 1 to 6, inclusive, is as follows:

45 The support 3 is mounted on the post 2. The screen 26 is suitably applied to the stencilled member and the panel 18, which may be of either of the forms disclosed in Figs. 5 and 6, is mounted in the stencilled member within the embossed portion 27 thereof. The fastening devices 11 may then be applied to suitable openings 28 and 29 in the stencilled member and support, respectively, for securing the panel and stencilled member to the support.

55 As light rays impinge against the sign, for example, those light rays issuing from the headlights of a motor vehicle at night, or light rays from the sun, for example, during the day, such rays strike the pebbled surface 19 or 24 of the panel 18 or 23, respectively, and due to the myriad convexities formed by such pebbled surface, a part of the surface of each individual pebble is adapted to catch and pass light rays into the interior or body portion of the panel, the light rays being disseminated throughout the panel to illuminate the same due to its transparent or translucent character and continuing their path to the inner or rear face of the panel for impingement against the lustrous element 21 or the prismatic inner face 25 of the panels for reflection from the plane face 21 and refraction from the prismatic face 25 again outwardly into the range of vision of the operator of the motor vehicle whose lights first generated the light rays.

75 Since the stencilled member is provided with

predetermined cutout portions or perforations forming the indicia, letters or words to provide a legend for the sign, the attention of the motorist is first attracted by the brilliance or luminosity of the sign and such motorist is subsequently informed of the legend of the sign to the end that the instructions on the sign may be followed and the purpose of the sign therefore accomplished.

The principal advantages in a sign embodying the features of the present invention are that light rays are received from practically any angle of incidence by the pebbled, and certain convex, outer surfaces of the panels, which serve to not only catch the light rays, but disseminate them by breaking up the rays and effecting a luminous appearance of the sign and panel thereof. The light rays, after entering the panel, are either reflected directly or refracted in further intensified or broken up condition by the prismatic contour of certain of the rear faces of the panels and emitted from the sign in magnified form in a multitude of directions in such a manner that the sign is visible to and attracts attention of persons within a wide range. The panels and indicia thereof, being formed of glass or synthetic resins, are strong and durable and resistant to the effects of the elements and the sign therefore maintains an attractive appearance and effective utility over a long period of time. Where parts of the sign have been damaged in certain of the forms of the invention, the indicia may be easily and quickly removed for ready replacement without loss of the effective life of the sign.

What I claim and desire to secure by Letters Patent is:

1. A sign of the character described including a support, a panel adapted to have light passed therethrough, a rigid member covering the panel and connected with the support for mounting the panel on the support, said member having cutout portions for exposing portions of the panel to provide a legend for the sign, and a separate wire mesh screen formed of relatively flexible fine wire mounted in said cutout portions for protecting the panel.

2. A sign of the character described including a support, a panel adapted to have light passed therethrough a rigid member covering the panel and connected with the support for mounting the panel on the support, said member having cutout portions for exposing portions of the panel to provide a legend for the sign, and a separate wire mesh screen formed of relatively flexible fine wire mounted in said cutout portions for protecting the panel, said screen having a lustrous finish.

3. A sign of the character described including a support, a panel adapted to have light passed therethrough, a stencilled member covering the panel and connected with the support for mounting the panel on the support, said member having cutout portions for exposing portions of the panel to provide a legend for the sign, a screen mounted in said member about said cutout portions for protecting the panel, and ribs mounted in the member at the cutout portions thereof for protecting the panel.

4. A sign of the character described including a support, a panel adapted to have light passed therethrough, a stencilled member covering the panel and connected with the support for mounting the panel on the support, said member having cutout portions for exposing portions of the panel to provide a legend for the sign, a screen mounted in said member about said cutout por-

tions for protecting the panel, and ribs mounted in the member at the cutout portions thereof for protecting the panel, said screen and ribs having a lustrous finish.

5. A sign of the character described including a support, a panel adapted to have light passed therethrough, a member covering the panel and connected with the support for mounting the

panel on the support, said member having cutout portions for exposing portions of the panel to provide a legend for the sign, ribs mounted in the cutout portions of said member for protecting the panel, and outwardly extending peripheral flanges 5 on said member about said cutout portions for protecting the ribs.

HORACE N. CARVER.
